[57] CLAIM

The ornamental design for a portable, collapsible ice fishing sled, as shown and described.

DESCRIPTION

FIG. 1 is a perspective view of a portable, collapsible ice fishing sled, with the fishing reels in the operable position, showing our new design;

FIG. 2 is a front elevational view thereof;

FIG. 3 is a side elevational view with the reels in the closed position and the latch cover in the open position, the opposite side being a mirror image thereof;

FIG. 4 is a bottom plan view thereof; and

FIG. 5 is a top plan view thereof.
